DESIGN FOR A STEERING WHEEL

Ermina R. Forbes, Washington, D. C.

Application April 2, 1940, Serial No. 91,419

Term of patent 14 years

To all whom it may concern:

Be it known that I, Ermina R. Forbes, a citizen of the United States, residing at Washington, in the District of Columbia, have invented a new, original, and ornamental Design for a Steering Wheel, of which the following is a specification, reference being had to the accompanying drawing, forming part thereof.

Fig. 1 is a plan view of a steering wheel, showing

my new design and Fig. 2 is a sectional view taken through the hub and one of the spokes of the steering-wheel on the line 2—2 of Fig. 1 looking in the direction of the arrows.

I claim:

The ornamental design for a steering wheel, as shown.

ERMINA R. FORBES.
